UNITED STATES PATENT OFFICE.

CLINTON E. WOODS, OF WATERBURY, CONNECTICUT.

TALKING-MACHINE.

1,396,083.

Specification of Letters Patent.

Patented Nov. 8, 1921.

Application filed June 26, 1920. Serial No. 392,137.

To all whom it may concern:

Be it known that I, CLINTON E. Woods, a citizen of the United States, residing at Waterbury, in the county of New Haven and 5 State of Connecticut, have invented a new and useful Improvement in Talking-Machines, of which the following is a specification.

This invention relates to talking-machines, and particularly to the manner of mounting the sound-conveying arm which supports the sound-box of such machines, and to the manner of assembling certain associated elements of such machines. 15 The principal object of this invention is to provide new and improved means for mounting the movable sound-conveying arm of a talking-machine so as to allow the usual freedom of movement of the sound-box carried by said arm and to coöperate with said arm in providing a smooth, sound-tight and unobstructed passageway for sound.

Another object of this invention is to provide new and improved means for connecting said movable arm to the stationary amplifying member or horn, which means may be quickly and easily assembled and taken apart.

In the preferred embodiment of the invention, there is provided in a talking-machine the usual supporting deck mounted in the cabinet in any suitable manner and having a suitably located circular aperture extending therethrough to permit the passage of sound 30 from a sound-conveying arm to an amplifying member or horn. To form the female member of a swivel joint for said sound-conveying arm, there is provided a flanged annular plate, of which the face portion 35 rests flat upon and is supported by said deck, and the flange portion projects downwardly through the aperture therein to form a tube. The male member of said joint comprises a second annular plate having a tubular portion extending through said aperture, being journaled in the downwardly-projecting tube-portion of said first annular plate and supported by the face portion thereof. From the upper face of said second plate, 40 there rises a marginal flange which is turned inwardly at its upper end to form a lip to engage the collared base of the sound-conveying arm, which is secured thereto by a suitable hinge.

55 The invention is susceptible of embodiment in various forms, one of which, for the

purpose of illustrating the invention, has been shown in the accompanying drawings, in which—

Figure 1 is a plan view of a sound-box, 60 sound-conveying arm and mounting therefor, in accordance with this invention; and

Fig. 2 is a side elevation, partly in section, of the supporting deck, sound-conveying arm and associated parts of a talking-ma- 65 chine.

Referring now to Fig. 2, there is shown the usual supporting deck 1 mounted in any usual manner in the talking-machine. A turntable 2, carrying record-tablet 3, is also 70 shown. Suitably positioned with respect to the turntable, there is provided an aperture 45 extending through the supporting deck 1. An annular plate 4 rests on the upper face of the deck, registering with the aperture 75 therein, and has a downwardly projecting cylindrical or tubular portion 5 fitting snugly within said aperture.

A second annular plate 7 rests freely upon said plate 4, and has a downwardly-projecting tubular portion 6, fitting freely within the bore of said portion 5. From the face 80 of plate 7 there rises a marginal flange 8 which is inturned to form a lip 9. The inner edge of the lip 9 is grooved so as to 85 hold a gasket 10 which may be of rubber or any usual packing-material.

A tubular sound-conveying arm 12 is provided at its base with a collar 11, which may be integral with the arm or may be secured 90 thereto in any suitable manner. The collar 11 is fitted into and yieldingly engaged by the gasketed lip 9. A portion of the flange 8 and lip 9 is cut away to receive an ear 13 which may project from the rear of collar 95 11 as shown in Fig. 1 or from the front of said collar and is slidably engaged by shoulders 14 of the cut-away portion. A pin 15 passes through corresponding holes in the flange 8 and in the ear 13 to provide a 100 fulcrum, about which the sound-conveying arm 12 may be swung on a horizontal axis, the pin 15, ear 13 and portion 8 forming together a hinge.

Supported at the outer end of the sound- 105 conveying arm 12 in any suitable manner, as by an elbow 16, there is provided the usual or any desired form of sound-box 17, here shown as a convertible sound-box equipped with two styli, one of which may be the 110 usual reproducing-needle and the other a jewel-point, so that records of any type may

be played by a simple adjustment of the sound-box.

The sound-conveying arm 12 is allowed the necessary range of movement toward 5 and away from the record tablet by the hinge 13, the contacting of its base portion 25 upon the plate 7 serving as a stop to limit its downward movement when there 10 is no record tablet to receive the stylus, while its upward movement is limited by the pressure of the gasket 10 on the collar 11. Freedom of movement for the arm 12 about a vertical axis is provided by the swivel joint 15 comprising the plate 7 which bears on the plate 4, the tubular portion 6 of which is journaled in the tubular portion 5 thereof. In order to decrease the bearing surface of 20 this swivel joint, the underside of the plate 7 may be countersunk and the inner side of the flange 5 may be countersunk as shown in Fig. 2. To limit the travel of the sound-box in a plane parallel to the record tablet, the outer edge of the plate 7 may be recessed to form shoulders 18 which abut against a 25 suitable stop as the screw 19, which is set in the plate 4.

To secure the neck 20 of the amplifying member or horn in its proper position relative to the deck 1, there is provided a flanged 30 annular plate 23 which registers with the apertures in said deck, and the inner edge of which is countersunk to receive the base of the tube 5 for facility in assembling. To secure the plates 4 and 23 to the deck, 35 there are provided screws 24 which pass through holes in the deck, which register with corresponding countersunk holes in the plate 4 and threads in the plate 23. The neck 20 fits snugly within the flange 22 of the plate 23 and is secured thereto in any 40 desired manner as by screws 21. The upper end of the neck 20 is of the same internal diameter as the tube 6 and is set so as to contact evenly with the lower end thereof, 45 thus providing a smooth passageway for sound.

In assembling the mounting for the sound-conveying members of the talking machine, the plate 4 is first set in place on the deck 50 1. The plate 23 to which the neck 20 is held secure is then fitted on the base of the tube 5. The plates 4 and 23 are then secured to the deck by the screws 24, adjustment for varying thickness of the deck 1 being 55 allowed by reason of the space between the base of the tube 5 and the face of the countersunk portion of the plate 23. The sound-conveying arm 12 is hinged to the plate 7,

which is then journaled in the tube 5. The stop 19 is then screwed in until its head rests 60 on the plate 7 and the assembling of the mounting is complete.

While the details of the preferred embodiment of the invention have been described with much particularity, the invention is not limited to the specific details shown since these may be varied within the terms of the appended claims, without departing from the spirit of the invention.

I claim—

1. A talking-machine comprising a sound-conveying arm, a supporting-deck having an aperture therethrough, an annular plate supported by said deck and having a tubular portion extending downward entirely 75 through said aperture, a tubular member journaled in said tubular portion and having an exterior annular collar resting flatly upon and supported by said annular plate, an upwardly-extending portion of said tubular member above said collar to engage the base portion of said sound-conveying arm, and a hinge positioned outside the bore of 80 said arm to secure the same to said upward extension of the tubular member. 85

2. A talking-machine comprising a supporting-deck having an aperture therethrough, an annular plate having a face portion resting on said deck and a tubular portion extending into said aperture, a tubular 90 member journaled in said tubular portion and having a flange-portion resting on the face portion of said plate, a portion of said tubular member extending upwardly above said flange portion inturned to form a lip, 95 a gasket in said lip, and a sound-conveying arm having a collared base pivoted to said upwardly-extending portion and yieldingly engaged by said gasket.

3. A talking-machine comprising a supporting-deck having an aperture therethrough, a sound-conveying arm, a collar at the base of said arm, an ear projecting outwardly from said collar, an annular plate having a tubular portion projecting downwardly through said aperture, and a second 105 annular plate supported rotatably upon said first plate and having a depending tube swiveling in said tubular portion, a marginal flange rising from said second plate 110 and inturned to loosely encircle said collar and having a cutaway portion to receive said ear, a pin to secure said ear to said flange, and a gasket to pack the space between said flange and said collar.

CLINTON E. WOODS.
